AIR-CONDITIONING APPARATUS

Gordon D. Harris, Freeport, N. Y., assignor to
 The Harris Air-Conditioner Corporation, New
 York, N. Y.

Application April 25, 1936, Serial No. 76,360

3 Claims. (Cl. 261—14)

Among the principal objects which the present invention has in view are: to provide an improved apparatus with means whereby small residential dwellings may be air conditioned at all times; to provide means connecting the apparatus to a hot water boiler or the like for receiving heat to be conditioned and then transferred to one or more rooms of a dwelling; to be enabled to receive air from one or more rooms for recirculation; to 5 condition air already in circulation in one or more rooms; to be enabled to condition air from outside before circulating the same; to provide means for dry conditioning air before circulating the same; to provide a plurality of spaced members 10 whereby a moist air condition is produced; to utilize means for regulating the amount of conditioned air passing into one or more rooms; to be enabled to use the apparatus during the several 15 seasons of the year; to secure simplicity of construction and operation; and to obtain other advantages and results as may be brought out in the 20 following description.

Drawings

25 Figure 1 is an elevation of my improved apparatus, and illustrating a schematic layout in the basement of a dwelling, and connected to a steam or hot water boiler;

Figure 2 is a top plan of the apparatus partly 30 in section and other parts broken away to show internal construction, the section being shown as taken on line 2—2 of Figure 3;

Figure 3 is a longitudinal sectional view shown as taken on line 3—3 of Figure 2;

35 Figure 4 is a transverse sectional view shown as taken on line 4—4 of Figure 3; and

Figure 5 is a perspective view partly in section of a unit through which a moist air condition is 40 produced.

Description

As will be seen from the drawings, and referring more particularly to Figure 1, my improved air conditioning apparatus is shown in a somewhat schematic installation arrangement. In 45 this showing it is to be understood that the conditioning unit is more particularly adapted for small residential dwellings, and is so constructed that it will take up minimum space in the cellar or basement of such a dwelling, and by virtue of inlet and outlet ducts, pipe connections, and dampers preferably manually operated, the conditioning unit may be used the year round. During 50 the cold weather, or winter season, the unit 55 can be easily connected to the usual hot water or

steam boiler provided for general heating purposes. Equally suitable corrections can be made should the heating medium be a small oil burner heater. As in the winter season, the usual procedure in dwellings is to keep the windows tightly shut, and with heat being transferred into rooms by virtue of radiators, very little moisture content exists, thereby causing a hot dry atmospheric condition. With use of my improved air conditioning unit, this dryness in the air is 10 eliminated. As is usual in the warm season of the year, dwellings must necessarily depend on outside atmosphere to enter the rooms to relieve hot and stuffy conditions. With the use of my improved air conditioning unit, this condition 15 likewise is remedied. Also, it can be said that the improved air conditioning unit may be used throughout the year and by virtue of a thermostat and humidostat the air in rooms preferably on the first floor can be kept at a normal temperature, having a comfortable moisture content 20 at all times. Provision likewise is made in the unit to eliminate excess humidity from the air before circulating into the rooms, thereby insuring an atmospheric condition free of too much 25 moisture.

As illustrated in Figure 1, there is shown in schematic arrangement a hot water or steam boiler 10 having a heating-medium return pipe 11 and a riser or heating-medium supply pipe 12, 30 with each of said pipes having standard valves 13, 13. Said boiler is used for the cold season of the year, and when not in use the heating-medium supply as well as the return may be completely shut off by virtue of the said valves 13, 13. 35 During the hot season of the year and when it is desired to use the apparatus for obtaining a cooled air condition, the pipes 11 and 12 can conveniently be connected to a refrigerating unit (not shown). However, for purposes of illustrating the invention, the general layout of the drawings is for cold weather purposes, and in which instance the pipes 11 and 12 are conveniently connected to the air conditioning unit 14 at one end thereof.

Said unit 14 preferably is made fast, by straps 40 15 or the like, to the underside of the usual floor beams 16 of the house construction, and may have one or more air inlet and outlet ducts. As shown in the present illustration, there is provided an outlet or circulating air duct 17 suitably spaced and leading upwardly into a room from the unit 14 and preferably at the end opposite from the end at which the pipes 11 and 12 are attached. A second air duct 18 leading from 45 50 55

the room to the unit 14 which for clarity will be referred to as the inlet or recirculating duct and preferably, in this illustration, to the left of the pipes 11 and 12 or to the forward end of the unit proper. Said recirculating duct is adapted for admitting the air heretofore conditioned in the room and allows for reconditioning that air in the unit and then again transferred into the room through the duct 17. If desired, air from an outside source may be used and conditioned, as may be desirable during the hot dry season of the year, and for this purpose a horizontally disposed duct 19 extends inwardly from outside the building and to the forward end of the unit 14. This duct, as installed, may be provided with the duct 18 directed laterally therefrom and extending upwardly through the floor of the room thereabove. Should the air from the room be desired for reconditioning, the air from the outside source may be completely shut-off from entering the unit 14, and for such purpose there is provided a manually controlled damper 20 in duct 19 between the outside opening and the lateral duct 18. On the other hand, if air from the outside is desired, as in the hot dry season, it is then preferred that the room air instead of being returned to be reconditioned, be shut off, and a damper 21 in the duct 18 may be closed. With the duct 18 closed to recirculating the air from the room and the outside damper 20 opened the air from the outside will then enter the unit. In either case, that is to say, when air from the room or from the outside is to be conditioned and then transferred into the room, a fan directly beneath the outlet duct 17 and suitably driven by a motor 22 obtains a positive circulation of the air. Said fan preferably is utilized to both draw the air into the unit to be conditioned and thence discharged into the room.

As heretofore described, the unit 14 may be used conveniently for conditioning air the year around, and means may be readily adapted to meet changes in atmospheric conditions. As in cold weather and with windows necessarily closed, the desire would naturally be for a warm air and preferably with a moist content. Such being the case, there is provided a thermostat 23 and having means (not shown) connected to a heat transfer chamber, to be hereinafter more fully described. Said thermostat by virtue of its connection to the heat transfer chamber will at all times control the temperature of the heated air before it passes on to be humidified. A humidostat 26 is shown for regulating the air received from the heat transfer chamber, and in this connection there is provided a plurality of dampers 24 and 27, within the unit 14. If the air to be treated is to receive a moist content the humidostat 26 provides means (not shown) for opening and shutting the damper 24 (Figure 3) within the unit by virtue of a lever 25 on the outside of said unit. On the other hand if a dry air condition is desired, particularly if the moist content is more than required, the damper 24 automatically closes, and the damper 27 opens by virtue of a lever 28 on the same regulating means under control of the humidostat 26. It is to be noted that the humidostat at all times controls the opening and closing of the dampers 24 and 27, and when the one damper, as 24 is open, the other damper 27 is closed, and vice versa. It is not deemed necessary to go into lengthy detail as to the construction of the thermostat 23 or humidostat 26 since they may be of any desired standard type and the operation will be readily understood by those skilled in the art.

In carrying out the invention and referring now more particularly to the unit 14, the same preferably is rectangular in shape and provides in the forward end one or more filters 29. Said filters may be of any suitable material, such as cloth, paper and so forth, and in use removes all dirt particles from the air entering the unit to be conditioned. As the clean air enters the interior of the unit, it is then subjected to an initial or preliminary condition, such as a heat transfer, which may be either heating or cooling. In the showing there is provided a heat transfer chamber 30 comprising upper and lower headers 31 and 32, with a plurality of staggered tubular members 33 connecting said headers. It is to the upper header 31 to which the supply pipe 12 is connected, and by virtue of the said pipe the heating medium, such as steam or hot water is constantly received. The heating medium is equally distributed and passes downwardly through the staggered tubes and outwardly into the lower header 32 there to be discharged into the pipe 11 and returned to the boiler 10. The heating medium flowing through the tubes 33 assures an even distribution of heat to the air after the incoming air has passed through the filters 29. Should a cooled air be desired, and as heretofore described, the flow of heat medium may be entirely shut off from the boiler 10 as by the hand valves 13, 13 with the pipes then utilized for receiving a refrigerant, ice water or well water. Said pipes 11, 12 are each provided with branch pipes for the cooling medium, one of which is the supply pipe 34 and the other is the return pipe 35, with each said pipe having a hand valve 36.

To further condition the air after it has passed through the heat exchange chamber 30, and to add moisture to the air before being transferred into the room, there is shown in Figures 2, 3 and 4, a plurality of spaced water chamber members 37. Said water chambers preferably are provided with longitudinal openings or tunnels 38 the walls of which are porous thereby permitting sweat or seepage to pass gradually therethrough and adhere to the tunnel surface. As the air is drawn through the tunnel, the moist condition created by the seepage will readily mix with the air and thus humidify the output. This humidification is regulated in accordance with the humidostat controlled damper 24. A reservoir 39 in the top of the apparatus supplies the water chambers with its aqueous content. The water in the reservoir is kept at a level above the tops of the respective water chambers 37, thereby assuring an ample supply in the said water chambers at all times. Said level is maintained by virtue of an inlet supply pipe 40 from the usual water supply source of the dwelling, a float 41 within the reservoir and a check valve 42. Water from the reservoir will flow to the water chambers by means of branch pipes 42a leading into the tops of each chamber respectively.

The water chambers 37 preferably are kept in upright position, and to prevent accidental displacement, are mounted on cross-pieces 43 (Figures 3 and 4) in a trough 44 with straps 45 secured to the cross-pieces and extending upwardly, around the tops of the chambers, then downwardly on the opposite sides and then held securely to the said cross-pieces. It is to be noted that the water chambers are set up from the bottom of the trough floor, thereby permitting excess moisture from the chambers to drip into the trough and be discharged through a drainage pipe 46. In order that the water in the cham-

bers 37 seep through the walls thereof and function properly, there is provided in the top of each chamber a small tube or air vent 41.

It is preferable that the air, as it passes through 5 and around the outside of the chambers 37, for its final conditioning, shall not pass over the top of said chambers, and means are provided whereby the air is prevented from so doing. Such means conveniently may be a plurality of baffle 10 plates 48, one from each chamber, and in the present arrangement the baffles extend transversely of the apparatus and from the tops of the chambers to the underside of the top wall of the apparatus. The conditioned air is thus stopped 15 from passing over the tops of the water chambers where humidification would be uncertain and very little at best. The air will be drawn through the tunnels and the sides and under the chambers towards the fan 49, past the moist 20 surfaces and will then be discharged upwardly and into the room through the discharge duct 17.

To meet other climatic conditions, such as the warm stuffy summer heat, the air is by-passed to 25 not contact the humidifying chambers 37. To accomplish this, the damper 21 is opened and the damper 24 to the humidifying chamber is closed. With the damper 21 in open position cool dry air 30 from heat exchanger 30 enters the dry air or by-pass chamber 50 by being drawn thereinto by the fan 49 and then upwardly and out into the room through the duct 17.

This air is by preference not recirculated back 35 into the apparatus as heretofore described, being prevented from so doing by closing the manually operated damper 21 in the duct 18 (Figure 1). However, the air instead of remaining in the 40 rooms may readily pass through open windows (not shown), and fresh air from the outside is received for conditioning through duct 19 by opening damper 20.

I claim:

1. An air-conditioning apparatus of the character described comprising an elongated housing through which air will pass for treatment, said 45 housing having an inlet and an outlet at opposite ends for said air, means for cleansing air at the inlet end, a heating medium comprising a plurality of vertically disposed tubes having upper and lower headers, the upper header adapted 50 to receive the heating medium to pass through the tubes and the lower header to receive the heating medium and to be discharged therefrom, and said housing having a plurality of porous water chambers each having tunnels 55 through, a water trough for supplying water to said porous water chambers whereby water may seep through the walls of the chambers adapted to humidify the air passing therethrough from the heating medium, and an air actuating fan 60 at the outlet end whereby cleansed air in heated condition is drawn through the housing and discharged from the outlet.

2. An air-conditioning apparatus of the character described comprising an elongated housing through which air will pass for treatment, said housing having an inlet and an outlet at opposite ends for said air, means for cleansing air at the 5 inlet end, a heating medium comprising a plurality of vertically disposed tubes having upper and lower headers, the upper header adapted to receive the heating medium to pass through the tubes and the lower header to receive the heating 10 medium and to be discharged therefrom, and said housing having a plurality of porous water chambers each having tunnels therethrough, a water trough for supplying water to said porous water chambers whereby water may seep through 15 the walls of the chambers adapted to humidify the air passing therethrough from the heating medium, and means in the top of the chambers for permitting accumulated air to escape from within the said chambers thereby presenting a 20 uniform distribution of seepage of the water through the said walls thereof, and an air actuating fan at the outlet end whereby cleansed air in heated condition is drawn through the housing 25 and discharged from the outlet.

3. An air-conditioning apparatus of the character described comprising an elongated housing through which air will pass for treatment, said housing having an inlet and an outlet at opposite ends for said air, means for cleansing air at the 30 inlet end, a heating medium comprising a plurality of vertically disposed tubes having upper and lower headers, the upper header adapted to receive the heating medium to pass through the tubes and the lower header to receive the heating 35 medium and to be discharged therefrom, and said housing having two chambers, one of said chambers having a plurality of porous water chambers each having tunnels therethrough, a water trough for supplying water to said porous water 40 chambers whereby water may seep through the walls of the chambers adapted to humidify the air passing therethrough from the heating medium, and means in the top of the chambers for permitting accumulated air to escape from 45 within the said chambers thereby presenting a uniform distribution of seepage of the water through the said walls thereof, and an air actuating fan at the outlet end whereby cleansed air in heated condition is drawn through the housing 50 and discharged from the outlet, and other means in the said chamber for closing it against receiving air to be humidified, and the other said chamber providing means for opening the same to receive cleansed air which has passed 55 through the heating medium and be discharged through the outlet end in a dehumidified condition.

GORDON D. HARRIS. 60
